LIQUID STORAGE APPARATUS

Wilbur G. Laird, Pleasantville, N. Y.

Application January 12, 1946, Serial No. 640,751

18 Claims. (Cl. 220—26)

1

This invention relates to improvements in the storage of liquids and more particularly of valuable liquids such as petroleum oils, and apparatus therefor.

This application is a continuation in part of pending application Serial No. 448,823, filed June 27, 1942, for "Method of Storing Liquids and Apparatus Therefor," now abandoned.

Large quantities of petroleum products are stored in tanks provided with floating roofs in which no attempt is made to save vapors, while still larger quantities of such products are stored in covered tanks without such roofs. Some closed storage is provided where there is good protection from loss by vaporization.

The present invention is directed to the object of improving and reducing the cost of storage by utilizing a floating roof type of tank in such a manner as to completely enclose or bottle-up the liquid at the level of the liquid in the tank. The improved method and apparatus may be applied to the storage of oil and other liquids in large tanks of the field type, and is suitable also for bulk storage and for underground storage at air fields and other points of use or supply.

One object of the invention is to provide an improved method of storing liquids by which the liquid in a tank is sealed-in or bottled-up at the level of the liquid regardless of the fact that different levels may be assumed at different times.

A further object of the invention is to provide an improved method of storing liquids in floating roof tanks in which the roof is permitted to move freely up and down during the filling or emptying of the tank, but in which the roof is locked to the tank wall and the liquid completely closed-in during the time the liquid is held under storage conditions.

An additional object of the invention is to provide an improved method of storing liquids in floating roof storage tanks in which the liquid is bottled-up in the storage tank and protected against contamination by the outside atmosphere, rain water, and other foreign materials.

Another object of the invention is to provide an improved apparatus for accomplishing the improved method.

According to the objects of the invention, the liquid is introduced into a storage tank, preferably of the upright cylindrical type which is provided with a buoyant floating roof. When the filling operation is completed with the roof floating freely on the surface of the liquid, the margin of the roof is locked with respect to the inside wall of the tank and the space between the two

2

enclosed with a clamping and gripping means so that the liquid is bottled-up, foreign matter is excluded, and vapor cannot escape around the rim of the roof into the upper atmosphere of the tank. If it is desired to introduce more liquid or withdraw liquid from the tank the roof is unlocked for the time required and then again locked at the new level.

In preferred form of the invention the roof is locked in place and the space between the edge of the roof and the tank is enclosed by inflating an annular tire or tube secured to the floating roof between its outside rim and the inside wall of the tank. This may be accomplished by hand operation or automatically. The floating roof or deck of tanks of relatively small diameter may be provided with or include a movable diaphragm or flexing portion, preferably of large area, to take care of the normal changes in the volume of liquid in the tank due to changes in temperature of the liquid when the roof is locked in place. In the case of large tanks other means are preferably provided to accommodate such volume changes. A suitable locking means other than a tire-type lock or grip may be used between the roof and tank wall.

It is acknowledged that various attempts have been made to enclose the space around floating roofs, for example by providing multiple liquid seals on floating roofs, as shown by the patents to Bohnhardt No. 1,666,525 and De Castro No. 2,125,771. Inflated and uninflated tubes, tires, etc., have also been proposed as marginal "seals" for floating roofs as shown by the patents to Bown No. 1,575,033; Glass No. 1,650,340; Haupt No. 1,735,461; Patrick No. 2,014,264; and Horton No. 2,085,752. However, in all of these instances the floating roof is left free to move up and down with the "seals" sliding freely on the tank wall as the liquid level changes and in no case is there any attempt to lock the roof or "seal" in place at any level. Flexing roof plates for floating and fixed roofs have been proposed and used in some instances as illustrated by the patents to Bailey No. 1,819,401; Wiggins No. 1,854,534; Wiggins No. 1,904,339 and Day No. 2,008,686. As far as known, however, such plate or diaphragm roofs are used exclusively for the accommodation of changes in the volume of gas or vapor collected under the roof.

The commercial development of the buoyant floating roof has resulted in almost universal adoption of the pontoon buoyant roof or deck which is somewhat smaller than the internal diameter of the tank, and provided with a margin-

nal "seal" (so-called) in an attempt to cover the space between the edge of the roof and the tank wall. This space is usually from six inches to a foot wide, to provide for the usual irregularities in the character of the tank wall, since steel tanks, such as upright cylindrical oil tanks frequently are not made and kept in the form of perfect cylinders.

The so-called "seals" used on floating roofs are not seals in the technical sense because, almost, if not all of them are made and used in such a way as to allow the escape of gases and vapors around the edge of the roof. Furthermore, it is generally believed in this art that provision must be made for the escape of gases and vapors around a floating roof. One of the most common "seals" used on floating roofs is an elaborate heavy structure including a ring of spaced vertical steel shoes (which slide along the wall of the tank), connected together with strips of water-proof fabric, the ring of shoes being supported by spaced pivoted supports from the roof so that the weight of the ring of shoes (or springs bearing against the shoes) causes them to bear against the tank wall. The space between the edge of the roof and the ring of shoes is closed with an annular piece of water-proof fabric, one edge of which is secured to the roof and the other of which is secured to the ring of shoes.

This so-called "seal" provides a metal-to-metal rubbing contact in which the shoes grind along the tank wall as the roof moves up and down in the tank with corresponding changes in liquid level. Gases and vapors formed from the liquid in the tank escape freely around the shoes along the tank wall and rainwater and other foreign matter enter the liquid along the tank wall in addition to the scale and rust ground off the tank wall by the steel shoes.

The marginal "seal" used with floating roofs or decks is never, as far as known, a seal at all but merely a kind of flexible loose cover for the space between the edge of the roof and the tank wall. (Horizontal flexibility is regarded as important because of tank wall irregularities.) These "seals" are never intended to function like the marginal "packing" of a dry gasholder, in which a gas-tight job is essential. Such gas holders, of course, are constructed with precision, so that they are smooth and of uniform shape and size throughout, whereas steel liquid storage tanks are not. Furthermore, dry gas holder packings and the shell walls thereof are thoroughly lubricated by a fluid lubricant applied under pressure to provide slip, to make the packing an effective seal against gas, and to prevent corrosion of the wall. It is of course "possible" to construct an oil storage tank on a suitable heavy foundation and with the precision necessary for the use of a packed floating roof, but the cost has always been and is likely always to be prohibitive. The structural materials and foundation used for dry gasholders would obviously be inadequate to withstand the deforming, settling and other effects which would be produced by a substantial column of liquid. Moreover, a "packed" piston put in an oil tank as a buoyant roof, if the tank shell were constructed to take one, would simply convert the "tank" into a combination oil tank and "dry" gasholder in which the piston might never float on the liquid because of the presence of vapor and gas above the oil. Pontoon, of course would not keep a packed piston "roof" horizontal on gas and vapor.

Oils, such as crude oil, stored in tank farms,

and around refineries, may not be moved for long periods of time, sometimes for months or a year or more. The same is true for oil products in bulk storage stations and other storage depots. Oil stored for such periods in ordinary tanks in water displacement type storage, and in tanks provided with the common type of floating pontoon roof is subjected to many hazards which can be avoided by the use of the present invention. Oil products in floating roof tanks are obviously contaminated with steel corrosion products, water and other foreign matter deposited in the tank from wind storms and other agencies. Rain water, dust, and tank scale enter such tanks around the roof "seal" because it is merely a loose affair, and because the roof and seal move up and down with all of the changes in level of liquid in the tank, even with the change of a few inches caused by the normal thermal expansion and contraction of the oil.

In most cases oil products which are contaminated in storage must be refined before use. For example, fuel oils of the bunker C type may emulsify with rain water to such an extent as to fail to conform to specifications. Finished gasolines and other products may require additional treatment or new supplies of inhibitor, etc., after being contaminated in storage.

Ordinary oil storage is always a serious fire hazard and experience has shown that present floating roof tanks are often fired.

The present invention provides an effective and inexpensive method and apparatus by which oils and oil products may be stored under bottle-tight conditions for any desired period of time and be safe from contamination and fire hazards.

From the following more detailed description of the invention it will be apparent that a new and advantageous method and apparatus for storing liquids has been discovered.

In the drawings forming a part of this application:

Fig. 1 is a vertical sectional view of a floating roof storage tank in which the features of the invention are illustrated.

Figs. 2 and 3 are broken vertical sectional views illustrating modified forms of portions of the apparatus shown in Fig. 1.

Fig. 4 is a broken vertical sectional view of a floating roof storage tank for liquids illustrating a form of control mechanism suitable for use with tanks of large diameter.

Fig. 5 is a broken plan view looking down on a portion of the mechanism shown in Fig. 4.

Fig. 6 is a view similar to that of Fig. 4 showing a portion of the apparatus in retracted position.

Fig. 7 is a broken view partly in section showing a modified form of a portion of the apparatus shown in Figs. 4, 5, and 6.

Referring to Fig. 1 of the drawings which illustrates the invention in connection with a storage tank suitable for use in bulk storage stations, the apparatus includes an upright cylindrical wall 2, a bottom plate 4 and a ventilated cone-type roof 6 for weather protection. This tank is provided with a floating roof of the deck-type which includes an annular rim section 8 which may be made of relatively heavy or rigid steel in the channel-like form shown, and a deck plate 10 secured to the lower horizontal portion of section 8 which covers most of the cross-sectional area of the tank and which is made of relatively thin sheet steel or other suitable material, in the form of a diaphragm adapted to flex upward

and downward, as indicated in broken lines. The diaphragm plate 10 may be made of stainless steel, especially for small tanks. The upper portion of the rim of the deck is provided with an annular flange 12 including a horizontal portion which fits the horizontal upper portion of the section 8. The annular flange 12 and the upper part of section 8 provides an annular outside pocket in which a fluid-tight hose or tire 14 is mounted and may be secured to the outside of the deck. The hose or tire may be provided with an integral fabric flange section which may be secured between the horizontal upper section of the element 8 and the horizontal section of the annular flange 12, or the tire may be fastened to the deck in any other suitable manner.

The hose 14 is preferably of endless tire type construction and adapted to be inflated with gas to such an extent that its outer surface will firmly grip the side wall of the tank and will lock the deck with respect thereto. The hose or tire 14 is also adapted to be deflated so as to release or unlock the floating deck during the withdrawal of oil from or introduction of oil into the tank, and means is provided for effecting the inflation and deflation of the tire 14 either automatically or by hand operation.

In filling the tank the oil, for example gasoline, is introduced through a line 16 which may be provided with a hand-operated valve 18, the handle of which is interconnected as shown, to a valve 20, for effecting the inflation and deflation of the tire 14. Assuming that the floating deck is locked at some level in the tank and it is desired to introduce additional oil into the tank, the opening of the valve 18 for this purpose operates valve 20 to open it to a vent 22 which connects through the valve 20 to a hose line 24 threaded over sheaves 26, 28 and 30, and connected through an automatic valve mechanism 32 and a line 34 to the tire 14. The hose line 24 is long enough to accommodate the full movement of the deck, the slack being taken up by the weighted sheave 28 which rides on the hose in the manner shown. The venting of the tire 14 releases the deck and allows it to float up freely until the desired amount of oil has been introduced. In closing the valve 18, the valve 20 is operated to cut off the vent 22 and admit gas through a supply line 35 at the desired pressure to inflate the tire 14. The gas from the line 35 flows through lines 24 and 34, to the tire 14, inflates it between the deck and wall to lock the tire onto the wall at the particular vertical position of the deck, closes-in the space between the deck and the tank wall and bottles-up the oil.

A hydrocarbon gas is preferably used in tire 14 in the storage of oils although the gas supplied through the line 35 may be air, nitrogen, CO₂, propane, ethane, natural gas, or other suitable gas. Bottled gases are available around oil refineries and readily obtainable for other tank locations. Many refineries have piped gas available as pressures sufficient to inflate the tire 14. The gas pressure used in the hose or tire 14 will depend to some extent on a number of local factors including the character of the tank wall and stored liquid, etc. The pressure can be decided upon in advance and governed so that the gas will be constantly supplied in the line 35 at the proper pressure which will not be high enough to over-strain the tank wall but will be sufficiently high to lock the deck or roof to the wall.

The tire 14 may be made like a bicycle or an automobile tire, and of any suitable materials

such as a fabric base and oilproof rubber, and may or may not include an inner tube. The tire 14 may include any type of tread adapted to increase the effectiveness of the grip on the tank wall and the tire may be fastened to the outside of the deck in any suitable manner so long as it is firmly secured thereto and in a fluid-tight manner when inflated. The inflation of the tire when merely set in an annular channel effects a seal to the deck as well as to the tank wall.

The showing in Fig. 1 of the drawings illustrates the condition of the apparatus with the tire 14 inflated and the valve 18 closed, the oil being effectively bottled-up as though it were in drums or "canned." There is no escape for vapors or gases, and no way for water, dirt or dust to enter the oil. Where the features of the invention are applied to an open-topped tank, the deck will be provided with a water drain line 20 as commonly used in the art. The flexible deck 10 is shown in a straight position but it may be flexed up or down in response to changes in the volume of the oil under the deck. The flexibility of the deck plate 10 is preferably adapted to accommodate the ordinary expansion or contraction of the oil due to changes in temperature. The temperature of a large body of oil changes very slowly even with abrupt changes in the atmospheric temperature.

30 The effect of unusual expansion or contraction of the oil under the deck, or possible leakage at some point, is automatically taken care of by the automatic valve 32 which is operated by the plate 10. The valve 32 is mounted in fixed position 35 with respect to the margin of the deck by being secured to a rigid cross piece 36 which extends across the deck and which is fastened to the elements 8 or 12 or both. The automatic valve mechanism includes a two-prong spring trip lever 38, a vent pipe 40 which may discharge outside the tank if desired, and a trip rod 42. One end of the trip rod 42 is fastened to the diaphragm 10 as shown, so that the rod is moved vertically with any flexing of the diaphragm. The other end of the rod 42 includes spaced lugs 44 and 46 with an intermediate positioning lug 48.

Assuming that there is considerable rise in the temperature of the oil bottled-up under the locked deck, or an excessive amount of vapor is formed; as the oil begins to expand the level will rise 50 between the deck and wall 2, compressing the gas therein. The plate 10 also starts to flex upward causing the rod 42 to operate the valve 32. The movement of the lug 48 merely tilts the trip lever 38 up a little and then disengages it, but the trip lever is then engaged by the lower lug 44 and is pushed up to a point where the valve 32 flips to open the line 34 to the vent pipe 40 and to cut off the supply of gas through line 24. 60 The lug 44 is set on rod 42 so that the valve 32 is thrown to vent when the deck plate 10 has been flexed up to the desired extent. As the valve 32 is opened to vent, the tire 14 is deflated and the deck released from the wall. The deck immediately assumes a normal position with the deck plate 10 approximately level. As the deck moves back to its normal position the intermediate lug 48 on the rod 42 engages the lower prong of the trip lever and throws the valve back to normal 65 so that the vent 40 is cut off and the tire 14 is inflated to lock the deck with respect to the tank wall again. The downward flexing of the deck plate 10 sufficiently to operate the valve 32, by contraction (or loss) of the oil in the tank, brings 70 the upper lug 46 in contact with the upper prong

of the trip lever 38 to throw the valve to vent and unlock the deck from the tank wall. After the tire 14 is deflated by either operation, the deck quickly assumes a normal position so that the oil in the tank is uncovered or "uncorked" for only such time as is required for the deck to reach normal position. The deflation of the tire 14 by the automatic operation of the valve 32 should be a rare occurrence, since the movement of the diaphragm plate 10 before the valve is tripped is sufficient to care for all normal variation in the volume of oil under the deck. Any vapor released upon the deflation of the tire 14 by the upward movement of the diaphragm 10 is quickly dissipated in the upper part of the tank and the concentration of hydrocarbon vapors even in the case of gasoline storage, will be unlikely to produce an ignitable mixture. When the diaphragm 10 flexes downward to the extreme point necessary to operate the valve 32, a small amount of air may pass below the deflated tire 14, but when the deck settles down, most of this will be pushed out before the tire can be again inflated.

The modified form of the apparatus illustrated in Fig. 2 shows an alternative arrangement for tripping the automatic valve 32 which is shown attached to the margin of the deck instead of to a beam across the center as in Fig. 1. In Fig. 2 the operating rod 42 is attached to a float 50 mounted in an open-bottomed chamber 52 at the edge of the deck. The diaphragm plate 10 flexes in the same manner as in Fig. 1 to take care of changes in volume of the liquid in the tank, but these changes act on the float 50 which in turn trips the valve 32 in the same manner and under the same conditions as described in connection with Fig. 1, the lugs 44 and 46 being set at the proper points to throw the trip lever 38 of valve 32 and deflate the tire 14 when certain maximum desired changes in the volume of oil in the tank occur.

The modified form of apparatus shown in Fig. 3 of the drawings illustrates the trip valve mechanism shown in Figs. 1 and 2 in connection with a slightly different form of tank and deck adapted to retain a layer of gas or vapor under the deck plate. In this figure a tank 53 is provided with a floating deck comprising a flexible-diaphragm deck plate 54 secured in fluid-tight manner to a marginal vertical plate 56 which extends above the plate 54 to give a deck somewhat similar to that shown in Fig. 1, and also extends below the deck plate 54 in the form of an apron adapted to trap and hold a layer of gas or vapors. The apron section extending below the plate 54 may be of any desired width.

In Fig. 3 the chamber 52 extends to a point slightly below the bottom of the apron so that liquid is always present in this chamber to operate the float 50 which in turn functions to trip the automatic valve 32 when the liquid in the chamber rises or falls to a predetermined extent. In Fig. 3 the tire 14 is mounted in an annular channel-shaped member 58 attached to the upper part of the annular plate 56. In this instance, the valve 32 is mounted at the side of the deck on the channel structure 58 as shown. If desired gas may be supplied to or removed from the space under the deck plate 54 by any desired means not shown if it is desired either to maintain or prevent the accumulation of a layer of gas. The presence of a gas layer tends to insulate the oil stored under the deck and

retard heat transfer from the deck plate. This is especially true in opentopped storage tanks.

Instead of using a float 50 to operate the valve 32 in the apparatus of Figs. 2 and 3, other suitable means may be employed such as for example, a bellows or a separate diaphragm, or other device adapted to utilize the variations in the volume or the pressure of the stored liquid.

The modified form of construction shown in Figs. 4, 5 and 6 comprises a tank having a wall 60 and provided with a floating deck or roof, the latter including an annular rim section 61 and a deck plate 62. The roof may be of pontoon construction or the rim 61 may extend below the plate 62 as in Fig. 3. The rim 61 has an upper inturned flange which serves to mount a tire or hose shown as comprising a casing 63 and an inner tube 64. The casing 63 is conveniently made of a sheet of material covering the inner tube and having its edges clamped between the horizontal sections of a pair of annular flange members 65, which form an annular pocket for the tire as in Fig. 1. The tire is supplied with and relieved of gas through a pipe 66 which terminates with a flange 67 in the inner tube 64.

The control mechanism shown in Figs. 4, 5 and 6 for automatically inflating and deflating the tire is illustrative of means adapted to operate in response to the up or down movement of the deck or roof. The mechanism is shown as mounted on a structural bracket 68 attached to the deck plate 62 and comprises a fixed cylinder 69 attached to the bracket 68, a long movable cylinder 70 having an attached or integral piston block 71 which operates in the cylinder 69.

A valve stem 72 is mounted axially in the cylinder 70 and carries sliding sleeve valves for controlling the flow of gas. Gas at the desired pressure is supplied from any suitable source to the control unit and to the tire through a flexible pipe 73, the pipe discharging into the right end of the cylinder 70 from which gas is also supplied to the pipe 66, also flexible. An irregular shaped cylindrical sleeve valve 74 is attached to the valve stem 72 in the right end of the cylinder 70, while a second sleeve valve 76 is attached to the stem 72 within the area of the piston block 71 by means of a solid wall 78 which serves as a piston and to block the direct flow of gas through the sleeve 76 and the cylinder 70. The left end of the valve stem 72 is squared and extends beyond the end of the cylinder 70. It operates in a spider-like head 80 fixed to the end of the cylinder 70, the member 80 having a square center opening which fits the square section of the valve stem and keeps it and the sleeves 74 and 76 from rotation relative to the cylinder 70.

The valve stem 72 extends through a suitable joint in the cylinder head at the right end of the cylinder 70 and is provided with a handle 81 and a spring 82 the latter engaging a washer and adapted to operate the valve stem under conditions described hereinafter. When the valve stem is pulled out by the handle 81 it may be locked in extending position by allowing the catch 83 to engage the washer used for retaining the spring.

The end of the cylinder 70 facing the tank wall 60 is provided with a pair of arms 84 which may be integral with the member 80. The ends of the arms carry a pivot pin and provide a pivoting support for a measuring wheel or disk 85 mounted on the pin between the arms. The

wheel 85 includes a rather wide arch shaped member 86 which carries a tread 88 of rubber or other suitable material for normally engaging the tank wall 60. Directly opposite the member 86 the disk 85 includes an integral fan shaped segment 90 of the same radius as the periphery of the tread 88. The segment 90 is part of a trip mechanism and normally engages the edge of a trip plate 91 attached to the end of the valve stem 72. A spring 92 tends to keep the disk or wheel 85 in the position shown in Figure 4 with the segment 90 centered on the plate 91. The cylinder 70 is kept from rotation by means of a guide rod 93.

The purpose of the mechanism shown in Figure 4 is to provide means for normally maintaining the tire firmly gripping or locked to the tank wall but to automatically release the pressure in the tire if the roof is caused to move up or down a predetermined amount. The measuring or tracking means including the disk 85 and the tread 88 are normally held by the mechanism in firm engagement with the tank wall so that the disk or wheel 85 will rotate on its axis if the roof moves up or down. The gas supplied through the line 73, under the conditions shown in Figure 4 of the drawings, is permitted to flow directly into the cylinder 70 through the opening shown in the sleeve 74. Gas is then also free to flow through the pipe 66 to the tire to inflate and lock it onto the tank wall.

The gas in the cylinder 70, which is at the pressure of the gas in the tire and pipe 73 operates on the surface of the wall 78 to force and maintain the valve stem 72 against the segment 90. At the same time gas flows through an opening 94 in the sleeve 76 and a matching duct 95 into the space to the right of the piston block 71. The space at the opposite end of the block is vented through a vent 75 and connecting duct 77. The gas pressure on this block forces the cylinder 70 to the left and maintains the tread 88 in firm engagement with the tank wall. As long as there is no substantial movement of the floating roof the control apparatus will remain in the position shown in Figure 4. With minor changes in the position of the roof the tire will be distorted and the segment 90 will slide along the trip plate 91.

When a substantial change in the volume of the liquid under the roof occurs, as for example a contraction due to a temperature drop, the roof moves down so that the upper flange 65 presses against the tire. At the same time the wheel 85 is rotated in a clockwise direction to move the segment 90 across the trip plate 91. Upon a predetermined movement the segment 90 moves below the trip plate 91 which with the valve stem 72 instantly shoots to the position shown in Fig. 6. The gas pressure against the piston wall 78 causes this instant action. The tripping of the valve stem 72 as described shifts the sleeves 74 and 76 to cut off the gas supply through line 73 and to open a vent 96 which permits deflation of the tire through the pipe 66. The shifting of the sleeve 76, closes the opening 94, opens a vent 97 to a duct 98 and opens a duct 99 to the left side of the block 71 so that the gas pressure available from the tire will move the cylinder 70 instantly to the right and retract the measuring wheel 85 from the tank wall. Fig. 6 shows the position of the mechanism immediately after the trip action occurred, with the tire still distorted.

When the tire deflates sufficiently it will as-

sume a normal position with respect to the flanges 65 and will be ready to be reinflated against the tank wall at a new level. In the tripping of the control mechanism the spring 82 is compressed so that it will be effective at the proper time to shift the valve stem 72 to the position of Fig. 4. The head of the cylinder 70 includes a friction catch 100, comprising a ball, a spring and an adjustment screw, for temporarily holding the valve stem 72 in the position shown in Fig. 6. The ball of the catch 100 engages a notch or recess 102 in valve stem.

After the tire is deflated so that it assumes its normal position, the pressure of gas against the piston wall 78 decreases to an extent sufficient to permit the spring 82 to move the valve stem 72 to the right, and with a snap action because of the friction catch 100 which releases the valve stem suddenly. The valve stem 72 then takes the position shown in Fig. 4, and the same is true of the wheel 85 which is rotated to position by the spring 92 as soon as the valve stem is shifted. The spring 82 is calibrated so as not to shift the stem too far. If desired a catch on the latch 83 may be used to limit the movement of the stem 72 by the spring 83. However, gas is soon flowing into the cylinder 70 from pipe 73 to keep it and the valve stem in position and to reinflate the tire in its new position on the tank wall.

If it is desired to vent the tire by hand as for example in a contemplated filling operation, the handle 81 is pulled to the right and the latch 83 set against the washer. This operation shifts the valve stem to cut off the gas supply and open the vent 96. It will be noted also that the shifting of the sleeve 76 to the right, from its position in Fig. 4, will uncover the venting duct 98 and supply gas through the duct 99 from an inlet 103 in the sleeve, so that the piston block 71 as well as the wheel 85 are shifted to the right away from the tank wall. After a filling operation is finished in this manner and the roof comes to rest the latch 83 may be released and the valve stem pushed to the position shown in Figure 4. In this position as explained above the mechanism operates to inflate the tire and maintain the tread 88 against the tank wall.

Instead of using the handle 81 directly it may be operated by remote control in the manner shown in Figure 7 of the drawings. In this figure a small pneumatic or hydraulic cylinder 104 is attached to the head of the cylinder 70. The cylinder mechanism includes a piston 105 returnable by a spring 106 mounted around a square shaft 107; to the end of which is keyed an arm 108. The horizontal section of the arm 108 includes spaced lugs 109 and 110 mounted on opposite sides of the handle 81. Liquid or gas is supplied to the cylinder 104, as for example as from some point on the ground through a line 112 which forces the piston 105 to the right so that the lug 109 will operate the handle 81 to move the valve stem to the right as in the hand operation described above. The handle 81 may be held in the extended position as long as desired by maintaining the pressure in the line 112. When the pressure is released the spring 106, in co-operation with the lug 110 will return the valve stem 72 to the position shown in Figure 4, which is the position also shown in Figure 7. The shaft 107 being square prevents rotation of the arm 108. The space around spring 106 is vented as indicated. The springs 82 and 106 act in compression to position the valve stem. In either form the apparatus may be tripped and reset by

hand. The line 66 is provided with a safety relief valve 114 to protect the tire.

The problem of providing a diaphragm such as shown in Fig. 1, for tanks of large diameter is avoided by the use of mechanism of the type shown in Figs. 4 to 7. A tank of 120 feet in diameter holding 30,000 bbls. of oil with a 40 foot oil column, for example may involve some difficulty with a diaphragm. Such a column of oil would expand about 2 inches for each 10° F. rise in temperature, and this would amount to about 320 bbls., which is some volume of oil to be taken care of by a diaphragm or to provide a diaphragm for.

In a large tank, an arrangement of the type shown in Figs. 4 to 7, permits the roof proper to move up or down a predetermined distance while the hose, tire or other clamping and gripping seal is locked to the tank wall and sealed to it and the roof. A tire or hose is useful because it can be distorted by the up or down movement of the roof. A tire having a diameter of about 8 inches may be substantially distorted to provide appreciable up and down movement of the roof proper and without causing the tripping of the control means. The tire or hose need not be fixed to the roof but may be retained between flanges such as 65, and therefore may partly roll when it is inflated between the tank wall and the roof, and the latter moves up or down to distort the tire.

The measuring wheel trip mechanism of Figs. 4 to 7 is responsive to a predetermined liquid level or volume change in the tank or to a corresponding change in vertical position of the roof caused by the liquid level or volume changes. The valve trip mechanism may be attached to the shell or other fixed part of the apparatus while the measuring shoe or tread 38 bears against a mast attached to the floating roof, either to a rigid part or to a diaphragm forming all or part of the floating roof.

The floating roof or deck shown in any of the views may be provided with marginal pontoons if desired. The deck of Fig. 3 for example can be provided with marginal pontoons under the plate 54 so that gas will collect and maintain a layer within the area surrounded by the pontoons. The plate 62 of Fig. 4 may be a pontoon plate. The use of pontoons with the deck will tend to keep the deck level. Other means for keeping the decks level may be used in connection with the apparatus of the present invention.

The means shown for unlocking the deck when the tank is to be filled or emptied, including the valve 20 and its connection to the valve 18 is merely illustrative of one means for accomplishing this result. It is not necessary that the valve 20 be operated from the hand lever of valve 18 since the valve 20 could be operated by hand, by the person charged with filling or emptying the tank. Even if the valve 20 were not operated to deflate or release the sealing means it would be unlocked by the automatic operation of valve 32 as soon as sufficient liquid is introduced or withdrawn. Outside manual operation in addition to the automatic feature has many obvious advantages however in any form of the apparatus.

The apparatus of the present invention is well suited for underground storage in which the tank may be of steel or of concrete. Water for displacement is not necessary. The floating deck effectively isolates the oil and keeps the oil more free from contamination than a water displacement system would.

The process and apparatus of the present in-

vention are particularly useful in connection with the long time storage of petroleum oil products such as for example in field storage tanks. Under such conditions, it will be apparent that the bottling-up of the oil will have substantially the same effect as if the oil were "canned" or stored in drums, since the oil will be kept free from contamination and substantial loss. The locking up of the oil in the manner described prevents the escape of the small amount of vapors which normally might be formed and therefore maintains a definite vapor pressure above the liquid which in turn retards or suppresses the formation of additional quantities of vapor. In present floating roof tanks the vapor is always free to diffuse out around the so-called seals and air is breathed in. Oil stored under the conditions described in connection with the present invention however cannot go through the breathing operations which take place in connection with oil stored in the usual floating roof tank.

It will be apparent to those skilled in the art that various modifications may be made in the apparatus for carrying out the improved method and that certain variations may be employed in effecting the improved process. Such changes are to be included within the scope of the present invention, as defined by claims.

Having described the invention in its preferred form, what is claimed as new is:

1. In a cylindrical floating roof storage tank for liquids which includes an upright cylindrical shell and a buoyant floating roof therein of slightly smaller diameter than that of the inside of the shell, improved means for preventing contamination of the stored liquid by the entry of foreign materials around the edge of the roof between it and the shell, comprising an inflatable and deflatable tire having a peripheral surface grip, the tire being mounted on the periphery of the roof in the annular space between the roof and the shell, said tire being connected to the roof in a fluid-tight manner and mounted thereon in such a way that upon inflation its peripheral surface grip will contact the shell and produce a fluid-tight joint, means for inflating said tire sufficiently to lock the roof with respect to the shell, and means responsive to predetermined changes in the volume of the liquid under the locked roof for deflating said tire and unlocking the roof from the shell.

2. In a cylindrical floating roof storage tank as defined by claim 1 in which said floating roof is provided with a flexible deck plate adapted to flex up and down from a substantially flat position and arranged to operate said deflating means.

3. In a cylindrical floating roof storage tank for liquids which includes an upright cylindrical shell and a buoyant floating roof therein of slightly smaller diameter than that of the inside of the shell, improved means for preventing contamination of the stored liquid by the entry of foreign materials around the edge of the floating roof and for locking the edge of the roof to the shell, comprising a locking and enclosing means engaging the periphery of the floating roof in a liquid-tight manner, said locking and enclosing means being adapted to completely close the space between the roof and the shell of the tank, and means for operating said locking and enclosing means to lock the roof with respect to the wall of the tank at any level therein, said operating means including mechanism responsive to predetermined changes in the volume of liquid under the roof.

4. In a cylindrical floating roof storage tank as defined by claim 3 in which means is provided for introducing liquid into the tank, and in which said introducing means is interconnected with said locking means and adapted to unlock the roof with respect to the tank wall when liquid is introduced into the tank.

5. In a cylindrical floating roof storage tank as defined by claim 3 in which said roof includes a flexible deck plate, and means connected with said deck plate for locking and unlocking the deck with respect to the tank wall.

6. In a cylindrical floating roof storage tank as defined by claim 3 in which said roof includes means for retaining a layer of gas under substantially the entire area of the floating roof.

7. In a storage tank for liquids including an upright cylindrical shell and a floating roof therein, an annular locking and sealing means attached to the outer portion of said roof for locking said roof onto and for sealing said roof with respect to the shell wall, and control means for releasing said locking means from its locking engagement with the shell wall, said control means including means responsive to a predetermined change in the volume of the liquid under the roof when the roof is locked to the shell wall.

8. In a cylindrical floating roof storage tank for liquids which includes an upright cylindrical shell and a buoyant floating roof therein of slightly smaller diameter than that of the inside of the shell, a clamping and gripping means connected to said roof between the roof and shell, said means including means for sealing the space between the roof and shell and for locking said roof onto the shell wall at its floating position, said gripping means including means for unlocking said roof with respect to said shell wall, said roof including a flexible deck plate adapted to be flexed up and down in response to increase and decrease, respectively, of the volume of liquid under the roof when the roof is locked in position in the tank, and connecting means between said flexible deck plate and said roof-unlocking means for operating said unlocking means when said deck plate flexes up or down to a predetermined extent.

9. In a cylindrical floating roof storage tank for liquids which includes an upright cylindrical shell and a buoyant floating roof therein of slightly smaller diameter than that of the inside of the shell, an inflatable and deflatable sealing means mounted on the periphery of the roof between the roof and shell, means for inflating said sealing means to cause it to firmly grip the shell and thereby bottle-up the liquid in the tank, said inflating means including a valve control mechanism for effecting the inflation and deflation of said sealing means, and means responsive to a predetermined movement of said roof up or down with respect to said shell for tripping said valve mechanism and thereby cause deflation of said sealing means.

10. In a cylindrical floating roof storage tank for liquids which includes an upright cylindrical shell and a buoyant floating roof therein of slightly smaller diameter than that of the inside of the shell, an inflatable and deflatable sealing means mounted on the periphery of the roof between the roof and shell, and means for supplying a gas for inflating said sealing means and cause it to firmly grip the shell wall, said gas supplying means including a trip valve mechanism having a means responsive to a predetermined change in volume of the liquid under the roof for tripping the valve mechanism, the mech-

anism of said valve having one position for maintaining gas pressure in said sealing means and at least one position for permitting the deflation of said sealing means.

5. In a cylindrical floating roof storage tank for liquids which includes an upright cylindrical shell and a buoyant floating roof therein of slightly smaller diameter than that of the inside of the shell, an inflatable and deflatable sealing means mounted on the periphery of the roof between the roof and shell, means for supplying gas to said means for its inflation, said gas supplying means including a trip valve mechanism adapted to be operated so as to release gas from said sealing means and effect its deflation, and means responsive to a predetermined vertical movement of said roof for tripping said valve and effecting deflation of said sealing means.

10. In a cylindrical floating roof storage tank for liquids which includes an upright cylindrical shell and a buoyant floating roof therein of slightly smaller diameter than that of the inside of the shell, an inflatable and deflatable sealing means mounted on the periphery of the roof between the roof and shell, means for supplying gas to said sealing means for effecting its inflation including a valve mechanism mounted on said roof, said valve mechanism including a measuring wheel normally operating on said shell, a valve stem arranged to be tripped by a predetermined rotation of said wheel, said valve mechanism being arranged so that upon the tripping of said stem said sealing means is opened to vent and said wheel is retracted from said shell.

15. In a cylindrical floating roof storage tank for liquids including an upright cylindrical shell and a buoyant floating roof therein of slightly smaller diameter than that of the inside of the shell and normally supported by the liquid in the tank, the improvement which comprises an annular sealing and gripping means attached in sealed relation to the periphery of the floating roof and having a surface normally sealed with respect to and gripping the shell wall, actuating mechanism connected to said gripping means for forcing and holding said surface in firm gripping engagement with the shell wall at the position of the floating roof in the tank, pipe means for introducing liquid into and for withdrawing liquid from the tank, and a control means for controlling said actuating mechanism, said mechanism being adapted to move the gripping surface of the gripping means to either of two positions, one in firm gripping relation to the shell wall and the other in released relation to the shell wall, said control means including means responsive to the introduction or withdrawal of liquid from the tank for causing said gripping means to move to said other position.

20. A storage tank as defined by claim 13 in which said control means includes means responsive to a predetermined vertical movement of the floating roof for releasing said gripping means.

25. A storage tank as defined by claim 13 in which means is provided adjacent said pipe means for operating said control means to release said surface of the gripping means from the shell wall.

30. In a cylindrical floating roof storage tank for liquids including an upright cylindrical shell and a buoyant floating roof therein of slightly smaller diameter than that of the inside of the shell and normally supported by the liquid in the tank, the improvement which comprises an an-

nular sealing and gripping means including an inflatable and deflatable means in sealed relation to the periphery of the floating roof and having a surface normally gripping the shell wall, actuating mechanism connected to said gripping means for moving and normally holding said surface in firm gripping engagement with the shell wall at the position of the floating roof in the tank, pipe means for introducing liquid into and for withdrawing liquid from the tank, a control means associated with and cooperating with the actuating mechanism and having one position for forcing the gripping surface into firm engagement with the shell wall and a second position for releasing the gripping surface from the shell wall, and means for actuating the control device to said second position in response to the introduction into or withdrawal of liquid from the tank.

17. In a storage tank for liquids including an upright cylindrical shell and a buoyant floating roof therein of slightly smaller diameter than that of the inside of the shell, an annular sealing and gripping means attached in sealing relation to the outer portion of the roof for gripping and sealing the roof with respect to the shell wall, means for causing said gripping means to grip the shell wall, said sealing and gripping means being adapted to permit limited vertical movement of the floating roof when said sealing and gripping means is in gripping engagement with the shell wall, and control means for releasing the gripping means from its engagement with the shell wall, said control means including means responsive to a predetermined vertical movement of the roof when the gripping means is in gripping engagement with the shell wall.

18. In a cylindrical floating roof storage tank for liquids which includes an upright cylindrical shell and a buoyant floating roof therein of slightly smaller diameter than that of the inside of the shell, an inflatable and deflatable sealing means mounted in sealed relation on the periphery of the roof between the roof and shell, means for supplying gas to said sealing means for effecting its inflation and sealing engagement with the shell wall, said sealing means being adapted to permit limited vertical movement of the floating roof when said sealing means is in sealing engagement with the shell wall, said means for supplying gas including a valve mechanism mounted on said roof, a trip means for said valve mechanism for releasing gas from said inflatable means, and operating means mounted on the roof and normally engaging the shell for operating the trip means in response to a predetermined movement of the operating means with respect to the shell.
